[57] CLAIM

The ornamental design for a vehicle running board, as shown and described.

DESCRIPTION

FIG. 1 is a front and left perspective view of a vehicle running board embodying the design;

FIG. 2 is a rear and left perspective view of a vehicle running board embodying the design; and,

FIG. 3 is an enlarged sectional view of the vehicle running board taken along line 3—3 in FIG. 2.

The broken line showing of a portion of a vehicle in FIGS. 1 and 2 of the drawing is for illustrative purposes only and forms no part of the claimed design.
